CABANA

Sam H. Vuncannon, Miami, Fla.

Application May 25, 1954, Serial No. 30,644

Term of patent 14 years

(Cl. D88—3)

Fig. 1.

Fig. 2.

Fig. 3.

Fig. 4.

To all whom it may concern:

Be it known that I, Sam H. Vuncannon, a citizen of the United States, residing at Miami, Florida, have invented a new, original, and ornamental Design for a Cabana, of which the following is a specification, reference being had to the accompanying drawing, forming part thereof.

Fig. 1 is a side elevational view of a cabana, showing my new design;

Fig. 2 is a front elevational view of a cabana, showing my new design;

Fig. 3 is a top plan view of Figure 1; and Fig. 4 is a front perspective view thereof.

I claim:

The ornamental design for a cabana, as shown.
